CLAIM

We claim the ornamental design for a handle, as shown and described.

DESCRIPTION

FIG. 1 is a perspective view of the handle, showing our new, original and ornamental design;

FIG. 2 is a front view thereof;

FIG. 3 is a back view thereof;

FIG. 4 is a side view thereof;

FIG. 5 is another side view thereof;

FIG. 6 is a top view thereof; and,

FIG. 7 is a bottom view thereof.

The broken lines represent the environment in which the article resides and forms no part of the claimed design.
